AND BATTERY CASE

Constantin P. Lent, New York, N. Y.

Application December 14, 1946, Serial No. 135,525

Term of patent 7 years

(CL. D61—1)

To all whom it may concern:

Be it known that I, Constantin Paul Lent, a citizen of the United States, residing in Manhattan, in the county of New York and State of New York, have invented a new, original, and ornamental Design for a Combination Portable Electric Motion Picture Camera and Battery Case, of which the following is a specification, reference being had to the accompanying drawing, forming a part thereof.

In my drawing:

Fig. 1 is a perspective view of a combination portable electric motion picture camera and battery case, showing my new design in an open condition.

Fig. 2 is a perspective view of the same in a closed condition.

I claim:

The ornamental design for a combination portable electric motion picture camera and battery case, as shown.

CONSTANTIN P. LENT.
